UNITED STATES PATENT OFFICE.

JOSEPH J. MICHALSKI, OF BUFFALO, NEW YORK.

PLAYING CARDS.

Application filed May 27, 1922. Serial No. 564,103.

To all whom it may concern:

Be it known that I, JOSEPH J. MICHALSKI, a citizen of the United States, residing in Buffalo, in the county of Erie and State of New York, have invented new and useful Improvements in Playing Cards, of which the following is a specification.

This invention relates to a card game which is more particularly intended for educational purposes.

Its chief object is to promote and encourage love of country and the principles for which it stands, and to familiarize the players with famous patriots and statesmen of the nation and other distinguished persons noted for their achievements in art, literature, music, science, &c.

A further object of the invention is to provide a game of this character which is instructive as well as interesting and entertaining.

In the accompanying drawings, Figures 1-12, inclusive, represent face views of one card of each of the various sets or books constituting the improved game.

In the preferred embodiment of the invention illustrated in the drawings, the game consists of forty-eight cards constituting twelve sets or books of four cards each. The numerals 1-12 inclusive each indicate one of the cards of a book. Each book is devoted to a given class of historic or other events or a department of human achievement. To this end each card of a book bears a title or heading indicative of one of such classes and a series of names or words related to that class. Each card bears as many of such names as there are cards in a book, there being four on each in the sample shown. These books are also combined in certain groups for a purpose which will hereinafter appear.

In the drawing, the titles or headings given the cards of each book are designated by the numeral 13 and include, for example, "The most esteemed presidents," "Golden names," "The knights of freedom," "The great scientists," "The genial writers and poets," "The watchwords of America," "Achievements," "Painting and plastic," "Noted women," "Music and drama," "The press," and "Statesmen." Disposed in a column under each title are the names or words 14 associated therewith, all the cards of the book bearing the same four names.

As shown, one of the names on each card of a given set is printed in a prominent distinctive manner, such for instance as the name "George Washington" of card No. 1, while the remaining three names are printed in italics or in some other appropriate contrasting fashion, it being understood that different names are distinctively displayed on the four cards of each book. To further distinguish the various cards in each book, especially while being held in a fan-like position in the hands of the players, a sign or symbol 15 is preferably placed on each card at the left of that particular name which is distinctively written. These signs may be of any appropriate form, but as shown in the drawings, preferably include the representation of a moon, star, sun and globe.

The several books, besides bearing different titles and related names, are also distinguished from one another in that they are provided with suitable emblems which may be symbolic of the book titles. Those books to which the cards designated 6 and 7 belong, bear single emblems 16 which are located in different positions on the cards, the emblems on the cards 6 being preferably located centrally above their titles 13 and the emblems on the cards 7 being placed centrally below the columns of names 14. The books composed of said cards 6, 7 will be considered as constituting the "first group." Those books including the cards 8, 9 and 10 constitute the "second group" and are provided with two similar emblems 17 which are located in different positions on the cards, the emblems on the cards 8 being located above their titles 13 and at opposite sides thereof the emblems on the cards 9 above and below the titles and columns of names, respectively, and the emblems on the cards 10 at diagonally opposite corners thereof. The books including the cards 11 and 12 constitute the "third group" and are provided with three similar emblems 18 which in this instance, may be located centrally above the titles of the cards. The books constituting the "fourth group" include cards 3, 4 and 5. The latter are provided with single emblems 19 which are located in the upper right hand corner of the cards. Besides these emblems, the cards of the books in this group are provided adjacent their side edges with fanciful borders 20, the borders on the cards of one book being of a different design from those on the other books of the group. The border on the left hand side of each card preferably extends substantially its full length, while the border on the opposite or right hand side extends only a part of the length of the card, 5 say from its bottom to a point substantially midway of its length.

It will be noted that the cards of each book in the "first group" are provided with one emblem, those of each book in the "second group" with two emblems, those of each book in the "third group" with three emblems, and those in the "fourth group" with a single emblem together with a distinctive border. This arrangement not only readily 10 distinguishes the books from one another, but also affords the further advantage of assisting the player in properly grouping the different books.

The books which include the cards 1 and 20 2 are separate and distinct from all other groups, the same being termed "special value" books and bearing the titles "The most esteemed presidents" and "Golden names," respectively. The emblems 21 on said cards 1 and 2 are located at their tops. In addition to its emblem, each card 1 is provided with a fanciful border 22, extending completely around its marginal edge, while each card 2 is provided with a fanciful 25 partial border 23 disposed in the same manner as the borders 20 on the cards 3, 4 and 5.

The rules of the game are as follows:

With a complete deck of forty-eight cards, 35 the game may be played by three, four, six or eight persons, but five persons may play as well by removing two books from the deck, say, one book from the "second group" and one from the "fourth group," so that 40 the cards may be equally divided among the players. The cards are thoroughly shuffled and then dealt to the several players in the usual manner. The dealer starts the game by asking some player for a certain named card included in a book which he intends completing. For example, say he has three cards of the "Statesmen" book, but lacks the one bearing "Theodore Roosevelt". It is this card for which he asks. If the 45 player who is asked for that does not hold it, the party at the left of the dealer in turn asks for a desired card and so on around the circle of players. Should a player obtain the card for which he asks, he is entitled to another turn. The game continues 50 in this manner until all of the books have been completed by the players.

The completed books have different 60 commercial values under certain conditions. If one gets all the books included in any one of the four groups heretofore mentioned, each book in the groups counts twenty. Each individual book forming only part of an uncompleted group counts ten, with the exception of the books constituting the "fourth group" in which each individual book counts twenty. The player who first completes one book of the "first group" adds fifty to his score and the player completing both books in said "group" adds one hundred to his 70 score. As before stated, the books containing the "Presidents" and "Golden names" are "special value" cards and serve to increase one's score by definite ratios, say two and three times as much, respectively. Any 75 player having more than one group at the end of the game is entitled to increase his score by one-half of the total number of counts obtained. Any player getting one book from each group of each of the several 80 groups adds fifty to his score. If a player obtains all of the four groups, he adds one hundred to his score. The player getting the last card of any book of the first group or the "Golden names" book is entitled to 85 fifty additional points.

While entertaining, this improved game is also educational in that it creates an interest in the historical and intellectual achievements of the country. By the arrangement and grouping of the books herein described the players are in effect striving for the principles set forth in the titles of the books and the names associated therewith, especially the books of the first group 95 and the "special value" books.

The book of "Achievements" is shown in the drawings as having a sub-heading of "sports," but I wish it to be understood that any other sub-heading, such as "national," 100 "societies," etc., may be employed together with names related thereto.

I claim as my invention:

1. A pack of playing cards, comprising a plurality of books arranged in groups, 105 each card of a book bearing a title indicating a department of human endeavor and a series of names related thereto, the titles and the related names being the same on each card of a book and one of the names on each card being distinctively displayed, the distinctive names being different on the cards of a book, the cards of each book being also provided with one or more like emblems and the emblems on the several books differing 110 from one another, the books constituting a certain group bearing a like number of emblems which are located in different positions on the cards of the several books in each group.

2. A pack of playing cards, comprising a plurality of books arranged in groups, each book including a number of cards, each bearing a title indicating a department of human endeavor, and a series of names related thereto, the titles and the related names being the same on each card of a book and one of the names on each card being distinctively displayed, the distinctive names being different on the cards of a book, the 115 120 125 130 cards of each book in certain groups being provided with one or more like emblems and the books which constitute a given group bearing a like number of emblems which are located in different positions on the cards of the several books in such group, the cards of the books in the other groups being provided with emblems and in addition thereto with contrasting marginal borders.

10 3. A pack of playing cards, comprising a plurality of books combined in groups and one or more books separate and distinct from such groups, each book of a group including a number of cards each having a title indicating a department of human endeavor and a series of names related to such title, the titles and the related names being the same on each card of a book and one of the names on each being distinctively displayed, the distinctive names being different on the cards of a book, and the cards of each book being also provided with one or more like emblems, the emblems of the several books differing from one another, those books which are separate and distinct from any group being "special value" books and bearing a certain increased numerical value to such groups. 20 25
